Application June 21, 1955, Serial No. 516,948

6 Claims. (Cl. 174—165)

This invention relates to glass insulator assembly units.

Assembly units of the kind to which the present invention relates comprises a glass insulator (sometimes referred to as an "upper shed") including a hollow head and a skirt, the skirt including a radial portion emanating from the base of the head, the interior of the head forming a socket which receives the hollow head of a lower shed also formed of glass and comprising a conical skirt, the two hollow heads being interlocked by an interposed cementitious lining. Within the inner head is interlocked in similar manner a mounting pin for the assembly, which pin is shrouded by an externally threaded copper ferrule.

Such an assembly is employed for carrying an electrical power cable, which latter is rested in a recess at the top of the head of the upper shed and is held in situ by a binding wire coiled about the head and about each part of the cable adjacent to the head.

The glass sheds are produced by a pressing operation effected in a mould on a charge of molten glass.

The head of the outer shed is usually shrouded by a suitable metal cap to hold it together if it should be fractured.

In co-pending application No. 486,962 is described an alternative method of effecting the restricted extraction of heat from the zone prior to chilling the glass to produce a toughened glass shed, this alternative method involving the application of a stream of air to that area in the skirt and near the head intended to form the zone which acts as the barrier in the manner already described.

In the process described in the said co-pending application there is a partial extraction of heat, effected as quickly as possible, from the annular body of glass in the skirt and near the head intended to form the zone, this extraction being effected immediately after the insulator has been withdrawn from the temperature equalising furnace by heat exchange with air directed on to the annular body of glass, so that the desired temperature difference between the glass in the annulus and the ambient glass in the insulator is obtained, and immediately a rapid chilling of the outer and inner surfaces of the insulator to toughen the insulator is effected.

In a second co-pending patent application No. 516,992 a further method of protecting the head of an upper shed is described in which the skirt is formed during the pressing operation with a delineated zone which is of somewhat less thickness than the ambient glass, as already described, and then the whole insulator is cooled by simultaneously and symmetrically directing gentle streams of cooling gas, for example air or steam, on to the whole external and internal surface of the insulator after it has left the temperature equalising furnace, so that a slightly toughened product results, that is to say, the degree of toughening obtained is not such as to produce "dicing" on a fracture occurring in the glass; but experiments have shown that an insulator thus obtained is approxi-

2

mately three times as strong as an insulator which is completely annealed in the well known manner.

The main object of the present invention is to devise a form of lower shed for insulator assemblies of the kind described which will assist in protecting the head of the upper shed against the effect of the impact of missiles projected from the ground, for example by catapults against the head when incorporated in a unit assembly.

In accordance with the present invention an insulator assembly unit including a glass insulator (upper shed), a lower shed and a mounting pin is characterised in that the glass insulator comprises a hollow head, a skirt having a radial portion emanating from the base of the head, an annular zone in the radial portion of the skirt, which zone has been thermally treated to prevent the propagation of a fracture initiated in the part of the skirt below the zone, through the zone upwards to the head, and the lower shed comprises a hollow head located within the head of the upper shed and a skirt emanating from the head of the lower shed in downward and outward direction to form an annular ledge below the said annular zone just below the level of the bottom edge of the insulator skirt, and an external annular cavity formed under the said ledge adapted to outwardly deflect missiles projected at the head of the insulator from ground level when the assembly is fixed in operative position.

The part of the skirt of the lower shed forming the wall of the annular cavity may be thermally treated to produce in the wall an annular zone adapted on toughening the insulator to prevent the propagation of a fracture in the lower part of the lower shed to the upper part thereof.

The zone in the lower shed may be delineated during the pressing operation, and to this end the wall of the cavity may be formed with an annular zone which is of somewhat less thickness than that of the ambient glass, the upper and under surfaces of the zone being confluent with the surfaces of the ambient glass, the zone thus formed being thermally treated as a precedent to toughening the insulator to form the zone into a barrier against the propagation of a fracture in the lower part of the lower shed to the upper part thereof.

In order that the present invention may be more clearly understood, a preferred embodiment thereof in an assembly unit including an insulator as an upper shed partially toughened as described in the said second co-pending patent application No. 516,992 will now be described by way of example, with reference to the accompanying diagrammatic drawing which is a central vertical section of the unit.

The glass insulator (upper shed) which is intended to be used for supporting power lines is a pressing which comprises a hollow head 1 including a recess 2, for a power line, at the top of the vertical axis 3—3, and an annular shoulder 4 below which is an annular recess 5 adapted to receive the usual binding wire for the line, the pressing also including radially outward (i. e. at right angles from the axis 3—3) from the bottom of the recess 5 a skirt 6, the bead being extended below the top of the skirt to produce the base 7 of the head.

Generally speaking, therefore, the hollow head is of cylindrical form with a recess top and sides, firmly set within the upper part of the skirt, which latter is thickest at the bottom and progressively decreases in thickness towards a zone in the upper part of the skirt as now to be described.

In the radial portion of the skirt 6 and near to the head 1 an annular zone 8 having a mean width of about half an inch is formed during the pressing operation, which zone is of minimum thickness in the middle, and symmetrically increases in thickness from the middle of the

zone, which latter is defined by the chain lines 9—9, the upper and under surfaces of the zone being confluent with the surfaces of the ambient glass. The skirt 6 progressively increases in thickness on the outside of the zone towards the rim 10 of the skirt, and on the inner side towards the base 7 of the head, the zone 8 having a convex face 11 on the outside and a concave face 12 on the inside.

The interior of the head 1 in known manner provides a socket 13 with two pockets 14, each extending substantially halfway around the interior of the head, said socket receiving the hollow head 15 of a glass lower shed comprising a skirt 16. A cementitious lining 17 to the head 1 fills the space between the heads 1 and 15 including the pockets 14 and makes an interlocking joint therebetween. The interior of the head 15 likewise forms a socket for the top of the usual mounting pin 18 which is shrouded by an externally threaded copper ferrule 19, the latter being interlocked with the head 15 by a cementitious lining 20 therein. Thus the pin 18, the lower glass shed 15—16 and the insulator 1—6 form an integral whole which carries a line indicated at 21 held to the unit assembly by a binding wire 22.

As clearly shown in the drawing, the skirt 16 of the lower shed is flared outwardly immediately from the base of the head 15 and extends outwards practically as far as the zone 3 in the upper shed (as viewed in plan) and forms an annular ledge 23 below the zone and in a plane just below the level of the bottom edge of the skirt 6 of the upper shed.

Immediately below the ledge 23 the skirt 16 is formed to define an external annular cavity 24 so devised that if hit by a stone, for example catapulted from the ground, the wall of the cavity will deflect the stone from its path of projection outwardly from the assembly or at least so that, if it hits the rim of the skirt 6 below the zone 8 any damage is very much restricted.

The cavity wall may be thermally treated to produce a zone 25 which then acts as a barrier if the lower shed is fully toughened as fully described in the aforesaid co-pending application 486,962 but the zone may be delineated in the same manner as zone 8 in the pressing operation by which the lower shed is produced, so that as a result of partially toughening the lower shed in the same manner as the upper shed, an effective barrier is constituted by the zone 25 to the propagation of a fracture through the zone.

In such arrangement the annular zone 25 is of somewhat less thickness than that of the ambient glass in the insulator.

By the present invention very effective protection is given to the upper shed of the unit assembly against fracture by missiles directed against it from ground level.

By utilizing the constructural forms of insulator sheds hereinbefore described a mechanically sound insulator structure is devised, after the pressed article has been subjected to the usual temperature equalising treatment and then cooled in the manner described, and an insu-

lator of sufficient strength is produced to carry not only the normal load of the line, but also the seasonal extra loads such as are produced by snow and other conditions derived from low temperatures.

We claim:

1. An insulator assembly unit comprising a glass insulator, a lower shed and a mounting pin characterised in that the glass insulator comprises a hollow head, a skirt having a radial portion emanating from the base of the head, an annular zone in the radial portion of the skirt adapted to prevent the propagation of a fracture initiated in the part of the skirt below the zone, through the zone upwards to the head, and the lower shed comprises a hollow head located within the head of the insulator and a skirt emanating radially from the head of the lower shed, the upper surface of the skirt emanating in an outward and then downward direction to form firstly an annular ledge positioned beneath the said annular zone at a level just below the level of the bottom edge of the insulator skirt, and then an external arcuate annular cavity opening under the said ledge adapted to deflect outwardly missiles shot at the head of the insulator when the assembly is fixed in position from ground level.
2. An insulator assembly unit according to claim 1, wherein the annular zone in the skirt of the glass insulator comprises glass toughened to a lesser degree than the ambient glass.
3. An insulator assembly unit according to claim 1, wherein the annular zone in the skirt of the glass insulator is of somewhat less thickness than that of the ambient glass, the upper and under surfaces of the zone being confluent with the surfaces of the ambient glass and the whole of the glass insulator being slightly toughened.
4. An insulator assembly unit according to claim 1, wherein the wall of the cavity is formed with an annular zone which comprises glass toughened to a lesser degree than the ambient glass.
5. An insulator assembly according to claim 1 wherein in the part of the skirt of the lower shed forming the wall of the annular cavity comprises an annular zone adapted to prevent the propagation of a fracture in the lower part of the lower shed to the upper part thereof.
6. An insulator assembly according to claim 1 wherein the wall of the cavity is formed with an annular zone which is of somewhat less thickness than that of the ambient glass, the upper and under surfaces of the zone being confluent with the surfaces of the ambient glass, and the whole of the lower shed being slightly toughened.
